UNITED STATES PATENT OFFICE.

JAMES E. HANLY, OF UNIONTOWN, PENNSYLVANIA.

RADIO TUBE SOCKET.

Application filed July 28, 1925, Serial No. 46,645. Renewed March 23, 1928.

My invention relates to a support or socket for electrical devices in general and is particularly adapted for vacuum tubes of the three electrode type, which, when used 5 in connection with radio telegraphy and radio telephony, whether it be employed as an amplifier, a modulator, an oscillator, a detector or for other purposes, and due to the elimination of the ferrule which surrounds the usual tube socket, effectually 10 eliminates dielectric losses and reduces absorptive losses to a minimum. One of the principal objects of my invention, therefore, resides in a very simple, inexpensive 15 and highly effective low loss radio tube socket. The scope of my invention extends to whatever construction may be defined by or included within the terms or language of the appended claims.

20 In the drawing:

Figure 1 is a side elevation illustrating my improved tube socket, showing a tube in position;

25 Figure 2 is a view in perspective of the socket member and

Figure 3 is a transverse sectional view, on the line 3—3 of Figure 2 looking in the direction of the arrows.

30 My invention, in the form or embodiment shown in the drawing and briefly described, 35 comprises a base, 10, which I have illustrated as consisting of two sections, 11 and 12, which may be formed of Bakelite, rubber, glass, porcelain or similar insulating materials.

A plurality of suitably spaced socket members, 13, which are preferably made of phosphor bronze, are carried by and adapted to pass through suitable openings, 14, located in the upper section, 12, of the base, 10. The tubular or socket members, 13, are each provided with an angular extension, 15, which is threaded on its outer ends as indicated at 16, for the purpose of receiving 45 suitable lock nuts, 17. The upper end of the tubular or socket members, 13, are provided with relatively narrow slots, 18, for the purpose of forming a perfect contact with respect to the usual lugs or leads, 19, of the 50 tube, 20. The slots, 18, also permit the tube, 20, to be readily inserted in its proper position or its removal therefrom, without danger of distorting the socket members.

It is to be understood, of course, that

when my improved sockets are employed for 55 sub-panel mounting in radio receiving or transmitting sets, that I have found it desirable to provide the binding posts on the bottom of the base, 10.

For the purpose of properly locating the 60 tube, 20, with respect to the base, 10, and for the additional purpose of preventing its accidental displacement with respect to the base, I provide a resilient member, 21, which is secured to the base, 10, by means of a 65 screw or in any other suitable manner. The upper end of the resilient member, 21, is curved slightly as at 22, in an outward direction, so that the tube may be readily guided into its proper position. An opening, 23, 70 is provided in the resilient member, 21, near the upper end thereof for the purpose of aligning with the usual pin, 24, of the tube, 20.

In order to readily locate the base, 10, to 75 the panel and to secure it thereon, I provide a pair of openings, 25.

Although I have illustrated the insulation base, 10, as consisting of the lower and upper sections, it is understood that I may 80 readily cast or mold the entire base in one piece, and effectually support the tubular members, 13, together with the terminals, 15, and the resilient member, 21, thereby providing a base that may be manufactured 85 upon a high production basis.

I claim:

1. A socket for vacuum tubes comprising a two-part insulating base and a plurality of terminal members connected therewith, 90 each of said members comprising a split-socket portion extended through and projecting above one part of the insulating base and a solid portion arranged between the parts of the base and projecting laterally 95 beyond one wall of the base to provide circuiting connectors wholly beyond the base, the projection of the socket portions above the base limiting the position of the connected tube to provide an air gap between the 100 tube proper and the base.

2. A socket for vacuum tubes comprising a two-part insulating base and a plurality of terminal members connected therewith, 105 each of said members comprising a split-socket portion extended through and projecting above one part of the insulating base and a solid portion arranged between the

parts of the base and projecting laterally beyond one wall of the base to provide circuiting connectors wholly beyond the base, the projection of the socket portions above the base limiting the position of the connected tube to provide an air gap between the tube proper and the base, and a member

carried by and projecting above the base to cooperate with a fixed part of the tube to secure the latter in place and indicate its proper circuiting relative to the socket members.

JAMES E. HANLY.
